POROUS RESILIENT BOBBIN

Joseph Annicq, Renaix, Belgium

Application February 28, 1951, Serial No. 213,251
In Belgium October 5, 1950

11 Claims. (Cl. 242—72)

1

This invention relates to a porous resilient bobbin, spool support or core upon which textile fibers, in the form of cheeses, cones or cakes of thread or yarn, or rolls of cloth or piece goods, are wound in preparation for and during fluid treatment of the fibers. More particularly it deals with an improved spring type of bobbin which is deformable or compressible in two different directions to compensate for elastic fibers and/or fibers which shrink or swell when wet, such as fibro, rayon, nylon, cotton, wool, flax, and like fibers.

Previously, spring type bobbins which were compressible axially or in one direction only, have been used, such as for example, like the spool support described in Joseph Annicq U. S. Patent No. 2,158,889 issued October 14, 1937.

It is an object of this invention to produce a simple, effective, efficient and economic bobbin which is compressible both axially and radially.

Another object is to produce such a bobbin which is, either cylindrical or frusto-conical, and is durable, long lasting and non-corrosive.

Another object is to produce such a bobbin which allows for the shrinking or swelling of yarns and/or cloth wound on it, without damaging the bobbin or obstructing the free passage of treating solutions through it and the fibers wound on said bobbin.

Another object is to produce a resilient bobbin which will permit loosening of the fibers at the center of the cake wound on said bobbin, so as to make the fibers softer and more permeable to treating solutions, as well as to permit easy removal of the bobbin from the roll of fibers without rewinding the fibers.

Another object is to produce a skeleton core forming a spool for textile yarns and rolls of cloth, which automatically produces an ideal cheese, cake or roll having a soft center for fluid treatment of cotton, wool and flax fibers without employing special adjustments for winding the yarn or cloth first loosely and then tighter on the bobbin.

Another object is to produce a spool support or bobbin having an expandable winding surface which will permit even thin and delicate yarns to be unwound therefrom easily to the last centimeter on the bobbin, without tangling or loss of any of the yarn near the center of the bobbin.

Still another object of this invention is to improve the spring type spool support described in the above mentioned Annicq Patent No. 2,158,889 so that it is compressible radially as well as axially.

2

In accordance with this invention, the bobbin is made of two wires sufficiently springy to keep their shape; one in the form of a helical spring, or truncated cone, which acts as the base frame or supporting spring for the bobbin, and the other, preferably a thinner or finer wire, which is wrapped loosely around each two adjacent turns of the helix of the base frame helical spring linking said turns together from one end of the base frame spring to the other. These links formed by the finer wire along each turn of the helix are alternately looped around the next adjacent turn on one side and then the other side of said turn to form a resilient tube of interwoven wire. The difference between this form of bobbin and that described in the previously mentioned Annicq patent, is that the second and finer resilient wire is much more loosely wound around the turns of the base helical spring, to permit considerable radial movement of the links or loops of the finer wire toward and away from the axis of the bobbin. Although the resiliency of the thinner wire which links the turns of the base helical spring together, is sufficient to keep the surface of the bobbin in its expanded position, and its loops uniformly spaced on the base frame spring, it may be desirable to place one or a pair of mandrels inside the bobbin while the thread, yarn, or cloth is being wound onto it, in order to wind the fiber material sufficiently tight and still maintain the expanded position of the bobbin until the fibers thereon are treated or ready to be treated.

The above mentioned and other features and objects of this invention and the manner of attaining them will become more apparent, and the invention itself will be best understood by reference to the following description of a specific embodiment of the invention taken in conjunction with the accompanying drawings, wherein:

Fig. 1 is a side elevation of an embodiment of a cylindrical bobbin according to this invention, as it appears without deformation and before any thread is wound thereon;

Fig. 2 is a vertical sectional view of a cake wound on a bobbin of the type shown in Fig. 1 which bobbin is maintained in its expanded and normal form by a pair of mandrels inserted inside said bobbin;

Fig. 3 is a plan view of the cake shown in Fig. 2 with the upper flange of the upper mandrel shown in section along line III—III in Fig. 2;

Fig. 4 is a vertical sectional view, similar to Fig. 2, but with said mandrels removed, showing

how the elasticity of the threads in the cake have radially compressed the bobbin;

Fig. 5 is a plan view of the cake shown in Fig. 4 illustrating how the contraction of the bobbin has loosened the threads near the center of the bobbin;

Fig. 6 is a vertical sectional view similar to Fig. 4 in which the cake and bobbin have been mounted on supports and axially compressed between two other identical cakes, preparatory to fluid treatment of the cakes; and

Fig. 7 is a side elevation of a frusto-conical bobbin, according to another embodiment of this invention.

Referring to Fig. 1, the base helical spring wire 10 has its two opposite ends welded or soldered to the next adjacent turn of the spring at 11 and 12, to form parallel annular ends for the bobbin perpendicular to the axis of said bobbin. At one of these ends, 11 or 12, one end of the second and preferably thinner and finer wire 15 is connected and then wrapped loosely around adjacent pairs of turns of the base helix spring 10, until the other end of the spring 10 is reached. The wire 15 forms links or loops 16 (see Figs. 2, 4 and 6) which are elongated and have substantially parallel sides bridging the distance between adjacent turns of the helix 10. These parallel sides are connected at their ends by broad U-shaped bends which sufficiently space apart said parallel sides to permit the loops 16 to be moved radially inwardly toward the axis of the helix 10, thereby decreasing the normal outside diameter of the bobbin as shown in Figs. 4 and 5 as compared to the diameter shown in Figs. 2 and 3.

One way of making the bobbins of this invention is to form the two wire springs 10 and 15 in separate spring bending or forming machines, and then to thread (as shown in Fig. 2 of the above mentioned Annicq Patent No. 2,158,889) the larger and stiffer base helical spring 10 through overlapped alternate links of the flattened helical spring 15 (which may have turns of gradually decreasing diameter at one end for the reason described below). This method is only best used for forming the main and central part (and possibly also one end) of the bobbin, that is, all but the last turn of the base spring 10 at one or both of its ends, in that the pitch of this last turn is decreased to zero by welding the ends of the spring 10 at 11 and 12 to form parallel ends perpendicular to the axis of the bobbin. Accordingly, this last turn at each end of the base spring 10, requires a spring 15 of turns of gradually decreasing diameter at both its ends. But, since such a shaped spring is difficult to thread onto a base spring 10, only one and preferably neither end of spring 15 is made with turns of decreasing diameter, and only an uniform spring 15 is made for threading onto the central portion of the spring 10. Then after this central portion of the wire 15 is in place, the ends of spring 10 are welded at 11 and 12 and the remaining one or both ends of the spring 10 are wrapped by hand with wire 15, either as an extension of the same wire forming the central part of the bobbin, or by a separate short length or lengths of wire connected to or at the ends of the wire 15 forming said central part of the body of the bobbin, so as to be substantially an extension of said main and central portion of the wire 15.

In order to illustrate the operation of the bobbin of this invention, reference is made to the use of a bobbin of the type shown in Fig. 1 for holding an elastic thread, such as nylon.

In Figs. 2 and 3 the bobbin of Fig. 1 has inserted into each end thereof mandrels 20 and 21 in order to maintain its natural and expanded shape, and then while these mandrels are in place, the nylon thread is wound on the outside cylindrical surface of the bobbin formed by the interwoven links of the wire 15. The mandrels 20 and 21 are shown to be cylinders with holes, such as 24 in mandrel 20, axially therethrough for the winding spindle (not shown) and with flanges 22 and 23, respectively, at one of their ends to rest against the ends of the bobbin.

After the cake 25 of nylon thread is wound on the bobbin, the mandrels 20 and 21 are removed, and the natural elasticity of the nylon thread compresses the bobbin, moving the links 16 axially inwardly to the position shown in Figs. 4 and 5. This movement loosens the windings of the central threads in the cake 26 of nylon thread as shown by the difference in shading between the sections of the cake in Figs. 2 and 4, and by the buckling of the threads at 27 in Fig. 5, so that the treating solution which is forced up through the center of the bobbin can easily pass between the links 16 and into the fibers of the cake to give an uniform treatment to all of the fibers in the cake.

The cake 26 and its bobbin are now ready for fluid treatment, so it may be stacked with other identical cakes in a column by means of special bobbin supports 30, such as shown in Fig. 6 and described in Annicq co-pending patent application S. N. 139,840, filed January 21, 1950. After these cakes are in position on a rod 31 they are axially compressed to prevent the treating solutions from passing between the cakes and not through them, and accordingly the cake of nylon is compressed to the form 28 shown in Fig. 6, and likewise the bobbin is longitudinally or axially compressed so that U-shaped ends of the links 16 are spaced at both their ends from the turns of helix 10, as shown. Thus Fig. 6 shows the bobbin of Fig. 1 deformed or compressed both axially and radially.

Fig. 7 shows a resilient bobbin according to this invention constructed on a frusto-conical helical base spring 70 (corresponding to spring 10 in Fig. 1) around adjacent turns of which is interwoven the link wire 75 (corresponding to wire 15 in Fig. 1). In this embodiment the number of links around the larger diameter turns of the base spring 70 are greater than those around the smaller diameter turns of said spring 70, which difference is gradually accounted for from one end of the base spring 70 to the other, in a degree depending upon the taper of the sides of the bobbin or the ratio of the difference in the diameters of each turn of said base spring 70.

In view of the two way flexibility of the bobbins of this invention, all types of shrinking or swelling fibers may be uniformly treated, without affecting the passage of the treating liquids through the bobbins. Also the permeability of the cheese, cone, cake or roll of fibers being treated is increased. Such advantages are of extreme importance in washing and dyeing rayon and fibro and similar fibers which swell when wet.

The wires of the bobbin of this invention may be coated or uncoated, and are preferably resilient which property is satisfied by an ordinary grade of hard wire. More preferably a stainless steel hard wire is used in order to resist corrosion by the treating solutions. The mandrels 20 and 21 may be made of any rigid material, of either wood, metal or plastic, as de-

sired, and they need not be non-corrosive, because they are not used in the treating solutions with the bobbin as the supports 30.

Although the cylindrical bobbin of Fig. 1 described above is about 16 centimeters long, both larger and smaller sized bobbins have been used for winding and fluid treating and dyeing fibrous materials from the finest of fibers and threads up to strips or sheets of cloth over a meter in width wrapped around bobbins of corresponding length and proportional diameters, and wrapped to proportional thicknesses of cloth corresponding to the material wrapped on the bobbin in Fig. 2.

Also the shape of the bobbin can be changed from cylindrical and frusto-conical as shown, to bobbins with irregular or curved profiles, without departing from the scope of this invention.

While there is described above the principles of this invention in connection with a specific embodiment thereof, it is to be clearly understood that this description is made only by way of example and not as a limitation to the scope of this invention.

What is claimed is:

1. A porous resilient bobbin for use in the textile industry, comprising a base helical spring of several turns of wire, and a spring wire helically wrapped around each two adjacent turns of said helical spring for the full length of said helical spring forming links between said adjacent turns, said links having broad U-shaped bends at their ends of an inside diameter greater than the diameter of the wire of said base spring whereby said links are enlarged radially to the axis of said helical spring to permit their radial movement on said helical spring.

2. The bobbin of claim 1 wherein said helical spring and wire are non-corrosive.

3. The bobbin of claim 2 wherein said spring and wire are of hard stainless steel wire.

4. The bobbin of claim 1 wherein said helical base spring is formed of wire of a greater diameter than that of the diameter of said springy wire.

5. A porous resilient bobbin for use in the textile fluid treating industry, comprising a helical metallic base spring of several turns, the ends of which are attached to the respective adjacent turns of said spring to form a hollow cylindrical shape with parallel flat ends perpendicular to the axis of said spring, and a wire loosely wrapped around two adjacent turns of said helical spring from the attachment of one of said spring ends to the other, forming a helix of interlaced links between adjacent turns of said helical spring, said links being enlarged radially with respect to the axis of said helical spring to permit their radial movement on said helical spring, whereby a porous tube is formed which is compressible both radially and axially to said helical base spring.

6. The bobbin of claim 5 wherein said links connecting one turn to the turn adjacent it on said helical base spring in one axial direction, alternate on each turn with the links connecting said one turn to the adjacent turn in the other axial direction on said helical base spring.

7. The bobbin of claim 5 including a mandrel having an outside diameter substantially equal to the greatest inside diameter of said bobbin for insertion into said bobbin to maintain said greatest diameter during winding of threads thereon.

8. A skeleton core forming a spool for supporting textile yarns and the like and comprising a wire bent to form a multiplicity of continuously connected loops having relatively straight side portions and relatively wide bends at the ends of and connecting said sides, said multiplicity of loops being disposed in a helical form having a series of convolutions wherein the ends of the loops of each convolution overlap the oppositely disposed ends of the loops in the next adjacent convolution, and a second wire extending helically through the overlapping end portions of the loops, said wide bends at said end portions having a diameter several times greater than that of the diameter of said second wire threaded through said end portions.

9. The core of claim 8 wherein said second wire is of spring metal.

10. A skeleton for forming a spool for supporting textile yarns and the like and comprising a wire bent to form a multiplicity of continuously connected elongated loops having relatively parallel sides connected at their ends by broad U-shaped bends, said multiplicity of loops being disposed in a helical form having a series of convolutions wherein the broad U-shaped bends of the loops of each convolution overlap the oppositely disposed broad U-shaped bends of the loops in the next adjacent convolution, and a second wire extending helically through the overlapping broad U-shaped bends of the loops, said broad U-shaped bends being sufficiently broad to space said parallel sides of said loops sufficiently apart so that said loops may move radially towards and from the axis of said core a distance over twice the outside diameter of said second wire.

11. The core of claim 10 wherein said second wire is of greater diameter than the first wire and lesser diameter than said broad U-shaped bends.

JOSEPH ANNICK.
